CLAIM

We claim the ornamental design for an air compressor, as shown and described.

DESCRIPTION

FIG. 1 is a top, front perspective view of an air compressor of the present invention.

FIG. 2 is a bottom, rear perspective view of the air compressor of FIG. 1.

FIG. 3 is a left, side perspective view of the air compressor of FIG. 1.

FIG. 4 is a side elevation view of the left side of the air compressor of FIG. 1.

FIG. 5 is a side elevation view of the right side of the air compressor of FIG. 1.

FIG. 6 is a front elevation view of the air compressor of FIG. 1.

FIG. 7 is a rear elevation view of the air compressor of FIG. 1.

FIG. 8 is a top plan view of the air compressor of FIG. 1; and,

FIG. 9 is a bottom plan view of the air compressor of FIG. 1.

In the drawings, the broken lines depict portions of the air compressor that form no part of the claimed design.
